UNITED STATES PATENT OFFICE.

LAUNA MATTHEWS, OF ATHENS, GEORGIA.

EMBROIDERY ATTACHMENT FOR SEWING MACHINES.

Application filed July 20, 1926. Serial No. 123,771.

This invention relates to an embroidery attachment for the presser foot of a sewing machine and has for its object first, to guide the braid coming from any direction to the needle of the sewing machine. Second, to provide an attachment that can be stamped out by a single operation of a stamping device and shaped.

With these and other objects and advantages which will be apparent as the description proceeds, I will now set forth the functions and features of my invention in connection with the drawing in which:

Figure 1 is a perspective view of a sewing machine, presser foot, the sewing machine needle and the attachment on the foot.

Fig. 2 is a bottom view of my attachment.

Fig. 3 is a top view thereof; and,

Fig. 4 is a view on the line 4—4 of Fig. 2. 20 The presser foot 1 of course has the usual notch (not shown) through which the sewing machine needle 2 passes. My attachment is S-shaped in general form and is provided in its tail arm 5 with a notch 3 which, when 25 the attachment is attached to the sewing machine foot as in Fig. 1, the notch 3 will be directly over the ordinary notch in the sewing machine presser foot. Directly opposite the notch 3 in the arm 5 of the presser foot is a 30 second notch 6. The middle portion 7 of my attachment extends from the body portion to a line forming the continuation of the edge of the arm 5 and extending back is a second arm 8 providing a slot in the attachment between the parts 7 and 8.

Extending to one side of the attachment is a clamping arm 9 which is bent under the other part of the attachment and terminates at the closed end of the slot 10, near the path 40 of the braid in its travel to needle.

In use the braid 11 is inserted over the arm 8 under arm 7 up through the notch 6 and down through the notch 3, and thence through the notch (not shown) in the sewing 45 machine presser foot. The attachment is then applied to the presser foot between the bent under arm 9 and the body of the attachment, and the braid will be held by the attachment as shown in Fig. 1 of the drawing.

50 It will be noted that the slot 12 in the attachment now has its open end closed by the presser foot and the braid 11 passing down

through the now closed slot 12 will be further directed under the arm 7 and to the notch 6 whether the braid 11 comes from the right 55 hand side of the needle or the left hand side or indeed from any other position. The braid 11, therefore, does not have to be held by the hand during the time that the needle is sewing it to the cloth below the foot. This is of 60 considerable advantage to the user, since it leaves both hands free to manipulate the cloth as the braid is being passed therethrough.

It will be seen that I have provided an extremely simple and yet efficient attachment, 65 efficient in operation and easily attached in position for work.

What I claim is:

1. A sewing machine presser foot having 70 thereon an S-shaped braiding attachment wider than the presser foot said braiding attachment comprising a tail arm, a second arm, and a middle portion and also having a bent-under arm for attaching it to said presser foot said second arm being sufficiently 75 longer than the width of the presser foot whereby, when the attachment is applied to said foot, the slot formed between the middle portion and said second arm will have its 80 normally open end closed but will leave an opening for the entrance of braid between the side of the presser foot and the closed end of the slot.

2. In combination, a comparatively narrow machine presser foot and a wider braiding attachment therefor said attachment having the general form of the letter S comprising a tail arm, a second arm and a middle portion and having an integral arm bent under the braider for attaching it to the presser foot the tail arm of the braider being notched on its side and the second arm and middle portion of the braider being separated by a normally open slot whereby, when the 95 wider braider is attached to the narrower presser foot and held thereto by the bent-under arm, the normally open slot is closed by the presser foot but leaves an opening between the side of the presser foot and end of 100 the slot through which the braid may enter and pass to the notch of the tail arm.

In testimony whereof I affix my signature.

LAUNA MATTHEWS.
